UNITED STATES PATENT OFFICE.

MAX JOHNSEN, OF OLYMPIA, WASHINGTON.

DESIGN FOR AN EGG-CUP.

42,084.

Specification for Design.

Patented Jan. 9, 1912.

Application filed July 13, 1911. Serial No. 638,383. Term of patent 7 years.

To all whom it may concern:

Be it known that I, MAX JOHNSEN, a citizen of the United States, residing at Olympia, in the county of Thurston and State of Washington, have invented a new, original, and ornamental Design for Egg-Cups; and I do hereby declare the following to be a full, clear, and exact description of the invention, such as will enable others skilled in the art to which it appertains to make and use the same.

My invention relates to an ornamental design for egg cups, the details of which are

fully set forth in the accompanying drawings which show a perspective view of my egg cup design complete ready for use.

I claim—

The ornamental design for an egg cup, as shown.

In testimony whereof I have signed my name to this specification in the presence of two subscribing witnesses.

MAX JOHNSEN.
